BY Tay, Oberle & Tay ATTYS.

UNITED STATES PATENT OFFICE.

RICHARD S. BRYANT, DECEASED, LATE OF CLEVELAND, OHIO, BY OTTO H. JOBSKI, OF CLEVELAND, AND JAMES H. GRISWOLD, OF EAST CLEVELAND, OHIO, SPECIAL ADMINISTRATORS, ASSIGNORS, BY MESNE ASSIGNMENTS, TO THE STANDARD PARTS COMPANY, OF CLEVELAND, OHIO, A CORPORATION OF OHIO.

METHOD OF FORMING DRIVING-LUGS ON FELLY-BANDS, RIMS, AND THE LIKE.

1,318,048.

Specification of Letters Patent.

Patented Oct. 7, 1919.

Original application filed February 26, 1916, Serial No. 80,739. Divided and this application filed September 21, 1916, Serial No. 121,477.

To all whom it may concern:

Be it known that we, OTTO H. JOBSKI and JAMES H. GRISWOLD, both citizens of the United States, and respectively residents of Cleveland and East Cleveland, county of Cuyahoga, State of Ohio, special administrators of the estate of RICHARD S. BRYANT, deceased, late a citizen of the United States, and resident of Cleveland, Ohio, (as by reference to the duly certified copy of letters of administration heretofore filed for the purpose of record will more fully appear,) believe said RICHARD S. BRYANT to have invented a new and useful Improvement in Methods of Forming Driving-Lugs on Felly-Bands, Rims, and the like, of which the following is a specification, the principle of the invention being herein explained and the best mode in which it was contemplated applying said principle, so as to distinguish it from other inventions.

The present improvements relating as indicated, to the manufacture of felly-bands, rims and the like, have more particular regard to the manufacture of demountable rims for automobile wheels, and of felly-bands adapted for co-operative use therewith. Still more particularly, such improvements relate to the formation on such rims, or bands, of so-called driving lugs, it being the object of the present improved method to stamp such driving lugs up from, and integral with, the material of the rim, or band, such lugs being severed along certain of their edges so as to form the necessary abrupt shoulders in order that a driving engagement may be secured between the wheel parts when assembled. To the accomplishment of the foregoing and related ends, said invention, then, consists of the steps hereinafter fully described and particularly pointed out in the claim.

The annexed drawings and the following description set forth in detail certain steps embodying the invention, such disclosed steps constituting, however, but one of various ways in which the principle of the invention may be used.

In said annexed drawings:

50 Figure 1 is a front elevational view of a

machine, or apparatus, adapted to form driving lugs in accordance with the improved method; Fig. 2 is a side elevational view of such machine, with parts appearing in section; Fig. 3 is a central vertical section of the dies forming part of such mechanism; Fig. 4 is a similar central vertical section taken at right angles to the section of Fig. 3; Fig. 5 is a plan view of a section of a typical rim, shown as provided with driving lugs formed in accordance with the present invention; Fig. 6 is a transverse section of such rim, taken on the plane indicated by the line 6—6, Fig. 5; and Fig. 7 is a longitudinal section of the same taken on the plane indicated by the line 7—7, Fig. 5.

Referring first to the driving lugs, or traction depressions, as they are sometimes called where thus formed integrally from the material of the rim, or felly-band, the detailed construction of one form of these lugs is fully illustrated in Figs. 5, 6, and 7. The lugs A', thus illustrated are the ones usually provided on the rim A, and are two in number, spaced longitudinally, that is, circumferentially of the rim, and adapted to interlock with the single driving place or lug on the felly-band (not illustrated). These two lugs are stamped from, and integral with, the material of the rim, and are severed from said rim along their juxtaposed edges so as to form abrupt shoulders a which are adapted to engage with the opposite sides of such driving plate on the felly-band. It will be further observed that the hole a' for the valve stem is, as usual, located midway between the driving lugs thus formed on the rim.

By the present improved method it is possible to simultaneously form not only both of the aforesaid driving lugs, but also this valve stem opening, a single operation accomplishing the results of a plurality of steps, whereas heretofore the opening has been required to be punched, and the two driving lugs then separately fitted, and welded or riveted on to the rim.

In its general aspect, the mechanism illustrated in the drawings as adapted to carry out the improved method may be regarded

as a punch press, the stationary die of which is mounted on a bed 2, while the movable die 3 is carried in a head 4 vertically reciprocable in an overhanging portion 5 of the frame that rises above such bed.

The stationary die 1, best illustrated in Figs. 3 and 4, is of composite construction, the several parts being suitably wedged or clamped in a holder 6 that is firmly seated in 10 the base of the machine. Such parts include a lower punch member 7 adapted to form the valve stem opening α' in the rim, and two bottom depression dies 8, as they may be called, one located on each side of such 15 punch, and facing the same, these last named members being adapted to form the depressions in the under face of the rim, which produce the bosses or lugs A' on the latter's upper face.

20 The parts of the movable die, which is likewise a composite structure, are similarly secured in a holder 10 suitably attached to the reciprocable punch head. Such parts include a centrally disposed upper punch 25 and shearing die 11 and two top depression dies 12. The latter are complementary to the bottom depression dies, and serve to form the upper faces of the lugs, or bosses, as they are stamped up by the action of the 30 lower dies.

As indicated by the term applied thereto, the central member 11 of the upper die is not merely complementary to the punch 7 in the lower die, being formed with a cylindrical bore 13 into which such punch is 35 adapted to fit, and through which the disk-like sections α^2 of the rim, cut by said punch, are discharged, but is also provided with two shearing edges 14 adjacent to the respective inwardly directed edges of the top 40 depression dies 12. The action of these edges 14, as the upper and lower composite dies are brought together, is to coöperate with the inwardly directed edges of the bottom 45 depression dies 8 to shear or cut the rim transversely on each side of the valve stem opening. Each coöoperating pair of depression die members 8 and 12 accordingly lift the cut edge of the boss or lug above the 50 normal plane of the rim, and thus provide the desired abutting edges α , as clearly shown in Fig. 7.

In order to assist in locating the rim for the operation of the dies, two guides are provided, a front guide 15 and a rear guide 16, in connection with the lower die-holder 6. The transverse form of these guides is best shown in Figs. 2 and 3, from which it will be seen that the one has an abrupt edge 55 to receive the corresponding straight edge α^3 of the rim, while the other is suitably curved to fit the beveled flange α^4 , with which demountable rims are ordinarily formed on their rear sides.

60 65 It will be understood, of course, that the

form of these guides may be varied to suit the character of the rim or band that is being operated upon.

The disks α^2 , cut out of the rim by the punch, represent the only waste material resulting from the operation, and such disks, as previously indicated, are discharged through the central opening, or bore 13, in the top punch member 11. The die-holder 10 is formed with a transverse slot 20 in 70 open communication with the upper end of this bore, so that after a sufficient number of operations, the topmost disk will be discharged into this slot, it being understood that the disks will fit the bore snugly enough 75 to be frictionally retained in place therein, without, however, preventing the inclusion of a fresh disk at the bottom, as successive blows are struck.

In such transverse slot 20, is a reciproca- 80 ble plunger 21 that is adapted to be operated, incidentally to the reciprocation of the movable head 4 of the punch, through the medium of a bell-crank 22 pivotally attached to a bracket 23 on the front face of said 85 head. The lower arm of this bell-crank has a sliding pivotal connection with one end of such plunger, while the upper arm of the crank, which is bifurcated, is provided with rollers 24 that run on inclined ways or cams 90 95 25, fixedly secured on the machine frame, adjacent to the path of movement of the punch head. Tension springs 26 serve to hold these rollers in contact with such cams.

Accordingly, it will be seen that, as the 100 head 4 is raised, the lower arm of the bell-crank is swung inwardly so as to project the plunger 21 toward the rear, and thus discharge from the slot the topmost disk α^2 , providing a sufficient number of disks have 105 accumulated in the bore of the top punch member. This slot, it will be observed, grows larger toward the rear so as to facilitate such discharge. On the contrary, as the head is lowered, the plunger is withdrawn 110 so as to permit the next disk to rise into the slot, and thus be ready to be ejected as just described.

It has been found that the method of manufacture exemplified in the operation of the 115 foregoing mechanism, in actual practice, is adapted to form the complete structure illustrated in Figs. 5, 6 and 7, namely both of the driving lugs and the valve stem openings, in a single operation, and such operations may follow very rapidly, so that this step in the manufacture of a rim, or band, of the type in hand, is accomplished with a celerity never realized with methods heretofore prevailing.

120 Other modes of applying the principle of the invention may be employed instead of the one explained, change being made as regards the process herein disclosed, provided the step or steps stated by the follow- 125 130

ing claim or the equivalent of such stated step or steps be employed.

The following is therefore particularly pointed out and distinctly claimed as the 5 invention:

The method of forming driving lugs on 10 felly bands, rims and the like, which consists in transversely cutting the material of such band, at two spaced points, the cuts being shorter than the width of the article in question, simultaneously embossing the portions of the material on the non-adjacent sides of the slits thus formed, so as to lift the corresponding cut edges above the normal plane of such article and form lugs in- 15

tegral with the latter but presenting opposed abrupt shoulders, and punching a hole in the portion of the material remaining between such slits, substantially as described.

20

Signed by us this 18th day of September, 1916.

OTTO H. JOBSKI,
JAMES H. GRISWOLD,

Special administrators of Richard S. Bryant, deceased.
